UNITED STATES PATENT OFFICE.

FRANCIS MURPHY, OF CHICAGO, ILLINOIS, ASSIGNOR TO WESTERN ELECTRIC COMPANY, INCORPORATED, OF NEW YORK, N. Y., A CORPORATION OF NEW YORK.

WIRE-DRAWING APPARATUS.

Application filed December 21, 1928. Serial No. 681,922.

This invention relates to wire drawing apparatus, and more particularly to a machine for stringing and positioning upon a rod or wire a series of dies preparatory to placing the rod or wire with the dies strung thereon in a wire drawing machine for drawing it down to its final size.

An object of the invention is to provide a machine of the above mentioned type, so equipped that the handling of the dies during the stringing operation is reduced to a minimum.

Another object of the invention is to provide a machine of the above mentioned type, which may be readily manipulated and controlled by the operator whereby an expeditious stringing of the dies on the wire at a minimum cost is accomplished.

A further object of the invention is to provide a machine of the above type which is simple in construction, inexpensive to manufacture, and economical in maintenance.

In accordance with the general features of this invention there is provided a rotatable drum and a stationary drum both mounted about a common horizontal axis. The rotatable drum is adapted to pull the rod or wire through a succession of dies individually. The stationary drum serves as a storage for the wire as the dies are successfully positioned thereon and also as a gauge for spacing the dies on the wire. Positioned above the axis of the drawing block and stationary drum is a combined die stop and storage member, and associated therewith is an adjustable auxiliary gauge which cooperates with the stationary drum to space the dies on the wire. The combined die stop and storage member along with the die spacing gauges provide a very efficient arrangement whereby the strung wire and dies may be transferred from and stored in close association with the drawing block as each die is strung upon the wire and the dies accurately spaced on the wire.

In the accompanying drawings,

Fig. 1 is a front elevation of a die stringing machine embodying the features of the invention;

Fig. 2 is a fragmentary side elevation thereof showing one stage of the stringing operation;

Figs. 3 and 4 are fragmentary front elevations of the machine showing several stages of the stringing operation, and

Fig. 5 shows the wire with the drawing dies strung thereon in the form in which it is removed from the machine.

The invention comprises essentially a combined die stop and die storage member and an auxiliary combined die spacing gauge and wire storage device which may be associated with the wire drawing apparatus fully disclosed in the co-pending application of Blount-Hernlund, Serial No. 566,222, filed June 6, 1922, which issued as Patent No. 1,621,309 dated March 15, 1927. In the accompanying drawing the invention is shown as applied to the wire drawing apparatus disclosed in the application above referred to and reference may be had to the said application for a full disclosure of the construction and functions of this apparatus.

As shown in the drawings, the operating parts of the machine are carried upon a frame 10 provided with a base 11. Within the lower part of the frame 10 is housed a driving motor (not shown), which is connected to a driving shaft 12 carrying a sprocket 13. The sprocket 13 through a link chain 14 drives a sprocket 15 positioned at the upper part of the machine upon a shaft 16, connected by suitable gearing and clutching mechanism (not shown), controlled by a foot lever 57 (shown depressed) for starting and stopping a drawing block 28 secured to the forward end of a shaft 22. The drawing block 28 carries a suitable gripper 29 mounted in a pocket or depression 30 formed at the forward end and about the periphery thereof. For turning the drawing block by hand a handle 52 is provided which is mounted on the wire gripper 29. A spiral semi-circular groove 27, shown in dotted outline in Fig. 1, of suitable width is cut in the drawing block 28, starting at the gripper and continuing for such a distance on a helix that will allow for the succeeding turns of wire clearing the gripper 29 as is usual in stringing machines and which is more fully illustrated in the co-pending application before mentioned. The gripper 29 is pivoted at 31 and in the rotation of the drawing block 28 it is limited in its movement about its pivot by stop pins 32 and 33 carried by the block 28. Mounted upon the frame 10 and about the shaft 22 is a wire storage and gauge drum 36, Fig. 2, of the same diameter as the drawing block 28. The drum 36 is provided with a flange 37

by which it is suitably secured to the frame 10.

Secured to the flange 37 of the drum 36 by screws 17-17 is a U-shaped bracket 18, the upper arm 19 of which is provided with a bifurcated portion 20, Fig. 2, extending at right angles thereto, and parallel to the axis of the drawing block and positioned directly thereabove. The bifurcated portion 20 is 10 adapted to serve as a combined die stop and storage device for the dies during the stringing operation and is disposed slightly to the vertical as shown in Fig. 2 for retaining the dies thereon. A vertical arm 21 of the bracket 18 is slotted as indicated at 42 and secured therein by nuts 23-23 are a plurality of horizontally disposed posts 25, 25 which serve as an auxiliary gauge and cooperate with the drum 36 to space the dies 20 on the wire, and as an auxiliary storage for the wire as the dies are successively strung thereon. By loosening the nuts 23 the posts may be adjusted vertically upon the arm 21. Secured to the upper arm 19 and 25 the lower arm 34 of the bracket 18 are posts 24 and 26 respectively, which are similar to the posts 25, 25 and serve the same purpose.

Pivottally secured to a bracket 48 secured to the face of the frame 10 is a spring actuated arm 49, Figs. 1 and 2, normally bearing against the periphery of the drum 36 adjacent its forward end. The arm 49 serves to hold the wire stored on the drum 36 from creening onto the drawing block 28 during 35 operation of the latter. A spring 50 holds the arm 49 against the drum 36.

A bracket 54 supports a die holder 55 which is adapted to swing about a pivot 56 on a radius suitable for allowing several 40 coils of wire as required to be distributed across the face of the drawing block 28.

Carried upon a stud 59 fixed to the front face of the frame 10 is a clutch tripping lever 62 provided with an upwardly projecting arm 63. The lever 62 upon being moved about its pivot stud 59 and toward the drum 36 causes a stoppage of the drawing block by the disengagement of a clutch (not shown) in the manner fully described 50 in the co-pending application before mentioned. An arm 64, on the lever 62, connects the latter to a foot lever 69, the arm 64 being secured to the upper end of a link member 65 by a pin and slot connection, the lower end of the link being connected to the foot lever 69. A spring 70 fixed to the upper end of the link 65 serves to hold it in its normal position, as indicated in the drawing. Upon a depression of the foot lever 69 60 the clutch may also be disengaged in a manner similar to the operation of the lever 62 hereinbefore mentioned.

A suitable mechanism for pointing the end of the wire to be strung with dies as 65 needed is carried on the frame 10 and is in-

dicated at 81. This mechanism and its operation is fully described in the co-pending application above referred to.

Operation.

In the operation of the machine a sufficient length of rod or wire is placed on the floor in the form of a long loop. The end 83 of the rod or wire is then inserted between a pair of the pointing rolls of the 75 pointing mechanism 81 to be reduced in diameter or pointed for a sufficient distance from the end to receive the first die to be strung thereon. After placing the first die, indicated at 85, on the wire, it is placed in 80 the die holder 55 with the end of the wire projecting through the die far enough to be gripped by the gripper 29 mounted on the drawing block 28, Fig. 1. The foot treadle 57 is then depressed to throw the clutch (not 85 shown) into engagement in the manner fully described in the co-pending application above referred to. The drawing block now starts to revolve and with it the gripper 29, which pulls the wire or rod through the die 90 85 held in the die holder 55 until a specified predetermined number of turns of wire have been wound on the drawing block 28, which will draw sufficient wire through the die to provide for the succeeding reductions 95 and proper locations of the other dies thereon, as shown in Fig. 5. The foot treadle 69 is now depressed, which causes the disengagement of the clutch (not shown) and thereby the stopping of the drawing block. 100 The wire wound on the drawing block is removed by the operator and the die 85 strung thereon is placed behind the bifurcated portion 20 of the U-shaped bracket 18, Fig. 3, which serves first as a die stop and second 105 as a die storage for all the dies as they are successively strung upon the wire.

After placing the die 85 behind the die stop 20 the drawn wire is passed under and over certain of the posts carried on the 110 U-shaped bracket 18 and then a specified number of turns of the wire are taken around the drum 36 by hand, depending upon the distance to be maintained between the die 85 just strung and the following die 115 95, the wire being held on the drum 36 by the arm 49, and thereafter the wire is looped behind the arm 63 on the clutch tripping lever 62, as clearly shown in Fig. 3, the operator holding the unstrung wire in his 120 hand.

The posts upon the bracket 18 along with the drum 36 serve as a gauge for determining the spacing between the dies on the wire and it will readily be seen that by taking a 125 turn or a certain number of turns around the drum 36, and then passing the wire over and under certain of the posts or around all of them, lengths of wire which are greater and less than coil lengths may be positioned 130

upon the bracket 18 whereby the distance between the dies may be gauged to a very fine degree. By positioning the posts at various points along the slot 22 in the bracket 18 the length of wire between the die, behind the die stop 20 and the drum 36 may be varied.

With the die 85 positioned behind the die stop 20 and the wire passed around certain posts and the required number of turns of the wire taken around the drum 36 to correctly position the following die on the wire, the operator points the end 83 of the wire again, if necessary, and a second die 95 is positioned thereon and placed in the holder 55 with the end of the wire gripped by the gripper on the drawing block.

The clutch is again engaged and the balance of the wire is pulled through the second die until all the slack is taken up and the wire becomes tight on the block 28 with the second die properly positioned on the wire with respect to the first die. At this instant the clutch is disengaged by the pull 25 on the arm 63 after all the slack in the wire is taken up. The movement of the arm 63 causes the disengagement of the clutch by moving the link 65 downward as is done by a depression of the foot treadle 69, in the manner fully described in the co-pending application before mentioned. Upon the second die 95 being properly positioned on the wire it is removed from the die holder 55 and a specified number of turns of the 35 drawn wire on the block 28 is slid back off the same and onto the storage drum 36, which operation is facilitated due to the fact that the block 28 and drum 36 are of the same diameter and in end to end engagement. The die 95 is then placed behind the die stop 20 adjacent the first die 85 positioned therebehind and the drawn wire is passed under and over certain of the posts carried on the U-shaped bracket 18, Fig. 4, 40 and then a specified number of turns of the wire are taken around the drum 36 by hand, depending upon the distance to be maintained between the die 95 just strung and the following die 96 all in a manner similar to that described in connection with the die 85. The wire is then looped behind the arm 63 of the tripping lever 62.

The end 83 of the wire is pointed again if necessary and the third die 96, fourth die 55 97, etc., are positioned thereon and placed in the holder and thereafter the same procedure is followed as has been described above until the proper number of dies which are to be used in reducing a given size, rod 60 or wire to a wire of required diameter have been accurately positioned upon the wire.

The arm 49 is given a shape at the end which bears on the drum to allow the wire as it is coiled around the drum to slip under 65 the arm against the action of the spring and

thereafter to be held and prevented from creeping onto the drawing block.

Upon the completion of the stringing of the dies upon the rod or wire and moving the arm 49 away from the drum, the strung wire may be removed from the drum 36 and upon wrapping the wire around the caps 70 stans on the wire drawing machine, the dies will drop into their proper holders.

The combined die stop and storage member along with the die spacing gauges, all closely associated with the drawing block provide a compact and efficient arrangement for a mechanism of this type, and one which results in reducing the time required 80 by an operator to complete a stringing operation.

What is claimed is:

1. In a machine for stringing dies upon wire, a die holder, a drawing block, a wire 85 storage means adjacent thereto, and a combined die stop and die storage member mounted adjacent said storage means, whereby the dies and wire may be transferred from the die holder and drawing block respectively and stored in close association with the drawing block as each die is strung upon the wire.

2. In a machine for stringing dies upon wire, a drawing block, a gauge member adjacent thereto, and an auxiliary gauge member mounted thereon, said gauge member adapted to receive wire thereon in coil lengths and said auxiliary gauge to receive lengths of wire which are greater and less than coil lengths after each die is strung for spacing the following die on the wire.

3. In a machine for stringing dies upon a wire, a drawing block, a stationary gauge drum in end to end engagement axially 105 aligned therewith, and an auxiliary gauge member mounted thereon, said gauge drum adapted to receive wire thereon in coil lengths, and said auxiliary gauge to receive lengths of wire which are less than coil 110 lengths after each die is strung for spacing the following die on the wire.

4. In a machine for stringing dies upon wire, a drawing block, a gauge drum adjacent thereto, and an auxiliary gauge mounted thereon, comprising a bracket member and a plurality of spaced pins mounted thereon, adapted to support the wire, said gauge drum adapted to receive coil lengths of wire wrapped therearound, and said auxiliary gauge to receive lengths of wire which are less than coil lengths after each die is strung for spacing the following die on the wire.

5. In a machine for stringing dies upon wire, a drawing block, a gauge drum adjacent thereto, and an auxiliary gauge mounted thereon, comprising a bracket member and a plurality of adjustable members adapted to support the wire and mounted on the bracket,

said gauge drum adapted to receive coil lengths of wire wrapped therearound, and said auxiliary gauge to receive lengths of wire which are less than coil lengths after each die is strung for spacing the following die on the wire.

6. In a machine for stringing dies upon wire, a die holder, a drawing block, a wire storage drum in end to end engagement and mounted axially therewith, and a combined die stop and die storage means associated therewith whereby the dies and wire may be transferred from the die holder and drawing block respectively and stored in close association with the drawing block as each die is strung upon the wire, said means comprising a bifurcated member above and parallel

to the axis of said wire storage drum and inclined slightly to the vertical.

7. In a machine for stringing dies upon wire, a die holder, a drawing block, a stationary gauge and storage drum in end to end engagement and mounted axially therewith for receiving coiled wire, a bracket attached to the drum, and a plurality of spaced pins mounted thereon and positioned for the selective looping therearound of portions of the wire of varying lengths less than the circumference of the drum.

In witness whereof, I hereunto subscribe my name this 13th day of December A. D., 1923.

FRANCIS MURPHY.
